[57] CLAIM

The ornamental design for a shoe upper and sole periphery, as shown and described.

DESCRIPTION

FIG. 1 is a perspective view of a shoe upper and sole periphery, showing our new design;
FIG. 2 is a right side plan view thereof;
FIG. 3 is a left side plan view thereof;
FIG. 4 is a front plan view thereof;
FIG. 5 is a rear plan view thereof; and,
FIG. 6 is a top plan view thereof.

The bottom of the shoe is not part of the claimed design.
